US00D844758S

(12) **United States Design Patent** (10) **Patent No.:** **US D844,758 S**
(45) **Date of Patent:** **** Apr. 2, 2019**

(54) **DEVICE FOR CONCEALING A FLANGE**

(71) Applicant: **WCM Industries, Inc.**, Colorado Springs, CO (US)

(72) Inventor: **William T. Ball**, Colorado Springs, CO (US)

(73) Assignee: **WCM INDUSTRIES, INC.**, Colorado Springs, CO (US)

(**) Term: **15 Years**

(21) Appl. No.: **29/599,496**

(22) Filed: **Apr. 4, 2017**

Related U.S. Application Data

(60) Continuation of application No. 29/561,022, filed on Apr. 12, 2016, now Pat. No. Des. 787,024, which is a continuation of application No. 14/332,148, filed on Jul. 15, 2014, now Pat. No. 9,453,329, which is a division of application No. 13/274,804, filed on Oct. 17, 2011, now Pat. No. 8,813,272.

(57) **CLAIM**

The ornamental design for a device for concealing a flange, as shown and described.

DESCRIPTION

FIG. 1 is a perspective view of the device for concealing a flange showing the new design;

FIG. 2 is a top plan view thereof;

FIG. 3 is a front elevation view thereof, the rear elevation view being a mirror image thereof;

FIG. 4 is a left elevation view thereof, the right elevation view being a mirror image thereof; and

FIG. 5 is a bottom plan view thereof; and,

FIG. 6 is a cross-sectional view thereof, taken along line 6-6 of FIG. 2.

The broken lines depict portions of the article that form no part of the claim.

1 Claim, 4 Drawing Sheets
